UNITED STATES PATENT OFFICE.

CHARLES L. BASTIAN, OF CHICAGO, ILLINOIS.

SODA-FOUNTAIN APPARATUS.

1,327,189.

Specification of Letters Patent.

Patented Jan. 6, 1920.

Application filed April 6, 1916. Serial No. 89,291.

To all whom it may concern:

Be it known that I, CHARLES L. BASTIAN, a citizen of the United States, residing at Chicago, in the county of Cook and State of Illinois, have invented certain new and useful Improvements in Soda-Fountain Apparatus, of which the following is a specification.

This invention relates to soda fountains and its object is, broadly, to improve the arrangement of the syrup jars with relation to the counter so that they will be accessible for obtaining syrup therefrom as required and at all times will be protected from wash or waste water or drippings from the counter.

Another object of the invention is to arrange the jars and the pump mechanism thereof so that they can be readily removed from the counter for cleansing and also to secure the jars in place in the counter by reason of the engagement of the pump mechanism with the counter.

A further object of the invention is to provide a pump mechanism operated by air pressure which may be obtained from the top of the tank of the carbonating machine or any other source of supply to provide a quick-acting pump for insuring a complete charge of syrup at each operation.

Other objects will appear hereafter in the detail description of the invention in the embodiments thereof illustrated in the accompanying drawings, in which—

Figure 1 is a sectional view on the line 1—1 of Fig. 2, showing my invention in its preferred form in place in the counter in full lines and pulled out from the counter in broken lines so that the pump mechanism may be removed from the jar;

Fig. 2 is a plan view of a portion of a counter with the top thereof removed;

Fig. 3 is an enlarged horizontal sectional view showing the pump mechanism as illustrated in Figs. 1 and 2;

Fig. 4 is a sectional view on the line 4—4 of Fig. 5 showing my invention embodied in a tilted syrup jar;

Fig. 5 is a plan view, partly in section, of the syrup jar illustrated in Fig. 4;

Fig. 6 is an enlarged sectional view of the pump mechanism illustrated in Fig. 4 but mounted underneath the plate;

Fig. 7 is a view, partly in section, illustrating diagrammatically the relative arrangement of a soda fountain counter and a

carbonating machine with my invention embodied therewith;

Fig. 8 is a detail fragmentary view.

Referring to the drawings and first more particularly to Figs. 1-3, 8 designates generally a counter which may be made of any suitable construction having a top 9 under which there is provided a plurality of compartments 10 to receive the syrup jars 11. Each syrup jar has a recess or well 12 in its bottom at the front thereof and the bottom of the compartment is provided with a raised portion 13 to support the jar. At the front of the compartment there is a hinged door 14 which may be opened to permit the insertion and removal of the syrup jar and pump for cleansing, filling and other purposes.

A pipe 15 for conveying air or gas under pressure to the syrup pumps extends transversely through all of the compartments 10 beneath the counter and is suitably supported in place, being provided in each compartment with a nozzle 16 having a spring-pressed valve 17 therein and a stem 18 projecting through the nozzle (Fig. 3) for a purpose hereafter described.

The pump mechanism of each syrup jar is preferably made as a single unit having all the parts thereof connected together so that it can be removed from the jar as a whole. This mechanism comprises a top plate 19 which is arranged to slide in guides 20 on the sides of the compartment to support the mechanism in fixed position within the jar. A face plate 21 rigid with the plate 19 closes the opening at the front of the compartment above the door 14. A pressure chamber 22 is mounted in the plate 19 and a piston rod 23, operating through the bottom of said chamber, carries a piston 24 at its upper end within the chamber and a plunger 25 at its lower end to operate in a charge chamber 26. This charge chamber is arranged in the recess or well in the jar and is provided with a valve 27 in its bottom and with a guide 28 engaging a notch in the plunger 25 to guide the latter in its movement in the charge chamber. A spring 29 arranged between the bottom of the pressure chamber and the piston therein normally holds the piston and plunger in elevated position, as shown in Fig. 1. A discharge pipe 30 is connected to and connects the charge chamber 26 with the plate 19 and a

is provided with a discharge spout 31 which projects outwardly through the face plate 21. A valve chamber 32 is arranged at one side of the pressure chamber 22 and communicates therewith through a port 33 (Fig. 3). The valve chamber communicates through ports 34 in one end 35 thereof with an inlet chamber 36 and within this chamber there is arranged a rubber socket 37 to receive a nozzle 16. The spring-pressed valve 17 normally closes this nozzle but when the pump mechanism is arranged in place the socket 37 is forced on the nozzle to make a tight connection and the end 35 of the valve chamber engages the stem 18 and unseats the valve 17 to permit pressure from the pipe 15 to enter the chambers 36 and 32 (Fig. 3). A piston rod 38 is arranged to operate through the other end of the valve chamber and through the face plate 21, being provided with a knob 39 on its outer end for convenience in operation. This rod carries two pistons 40 and 41 and the valve chamber is provided with a by-pass 42 and an exhaust port 43.

In normal position the valve 17 is unseated and the pistons 40 and 41 are projected forward, as shown in Fig. 3, by the pressure behind the piston 40. When it is desired to obtain a charge of syrup the piston rod 38 is pushed inward until piston 41 shuts off the exhaust port 43 and piston 40 is positioned with reference to the by-pass 42 to permit pressure to pass through the chamber 32 between the pistons and through port 33 into pressure chamber 22 above the piston 24 therein. The piston 24 is pressed downward against the spring 29 and the plunger 25 forces the syrup out of the charge chamber 26 through pipe 30 and discharge spout 31. When the knob 39 is released the pressure behind pistons 40 and 41 will force them to forward position permitting the pressure between the pistons and in the pressure chamber to escape through the exhaust port 43, whereupon the spring 29 will return the piston 24 and plunger 25 to normal position. The action of the parts will be quick and cause the charge of syrup to flow from the spout 31 in a steady stream. The charge chamber automatically refills because it is located at the lowest point in the syrup jar.

In this construction, (Figs. 1-3) the syrup jar is entirely covered by the top of the counter, as shown in Fig. 1, the only exposed parts thereof being the knob 39 and the nozzle 31 so that the jar is entirely protected against waste water and washing water flowing or dripping from the counter. This I consider a very important feature of my invention since it is highly desirable to maintain the syrup jars in a clean and wholesome condition and the contents thereof free from contamination and also because

waste or washing water or drippings from the counter are liable to enter the jars if permitted to flow over any part thereof as has been customary to a very large extent heretofore.

To remove the jar for cleaning or to refill the same or for any other purpose, the door 14 is opened and the pump mechanism is pulled outward with the jar until the plate 19 is free from the guides 20, (shown in broken lines in Fig. 1) whereupon the pump mechanism may be removed from the jar. By the time the socket 37 is disengaged from the nozzle 16 the valve 17 has seated to prevent the escape of pressure from the nozzle.

In Figs. 4—5, I have shown my invention embodied in a familiar form of tilted jar in a counter 44 having a comparatively narrow top 45. The jar 46, which may be made of any suitable material, is supported in an inclined position and the pump mechanism (which corresponds in all substantial respects with that heretofore described and is designated generally 47 to avoid further detail description) is mounted in the plate 48, the upper edge of which is arranged to fit snugly against the rear edge of the counter to form a close joint therewith. In the construction of Fig. 6 the pump mechanism 49 is mounted on the underside of the plate 50 which is intended to abut snugly against the rear edge of the counter in substantially the manner illustrated in Fig. 4. In the construction of Fig. 4 and Fig. 5 the valve chamber 51 is connected by a pipe 52 with the inlet chamber 53, which pipe enters the valve chamber above its bottom and serves the same purpose as the by-pass in the construction of Figs. 1-3. While I prefer the construction of Figs. 1-3 it will be observed that in the construction of Figs. 4-6 the syrup jar is also, to a very considerable extent, protected against waste or washing water or drippings entering the jar. In the latter constructions the pump mechanism is wholly protected and the jar is completely covered by the plate, the only openings therein being those provided for the piston rod 54 and the nozzle 55.

I may obtain air or gas pressure for operating the pump from any suitable source of supply. I may take this pressure from the top of the tank 56 of the carbonating machine by connecting the pipe 15 therewith, as shown in Fig. 7. This pipe should be provided with a valve 57 so that pressure may be shut off entirely from the syrup jars and also with a reducing valve 58 to reduce the pressure as desired. By this means I not only obtain pressure for the operation of the syrup pumps by means constituting a part of a soda fountain apparatus but also remove the air which accumulates in the top

of the carbonating tank and avoid the necessity for snifting.

My invention provides a soda fountain apparatus of simple construction in which the syrup jars are wholly protected from water or drippings from the top of the counter entering the jars and enables them to be kept in a sanitary condition, at the same time providing a compact arrangement of parts with a wide top for the counter completely covering the jars in the preferred form of the invention. With the exception of the charge chamber plunger the operative parts of the pump mechanism are entirely protected from contact with the syrup and this enables the pump mechanism to be easily cleaned. The pump mechanism is engaged with the sides of the compartments when arranged in place in the jar and this arrangement keeps the jar in place in its compartment wholly inclosed with the exception of the knob for operating the pump pistons and the discharge end of the nozzle, both of which are conveniently located for use. By taking the pressure from the top of the carbonating tank the cost of maintenance is reduced to a minimum and the necessity for snifting the machine to let out the air which accumulates in the top of the tank is avoided.

I am aware that changes in the form, construction and arrangement of parts may be made without departing from the spirit and scope of my invention or sacrificing any of the advantages thereof and I therefore reserve the right to make all such changes as fairly fall within the scope of the following claims.

I claim:

- 40 1. A soda fountain apparatus comprising a counter having a plurality of compartments therein, syrup jars removably supported in said compartments, a pump and actuating mechanism therefor in each jar adapted to deliver a measured charge of syrup therefrom, means for supplying fluid under pressure from a single source of supply to actuate the mechanism of said pumps, and means automatically operated by the removal of a jar from its compartment to prevent escape of the fluid pressure.
- 45 2. A soda fountain apparatus comprising a counter having a plurality of compartments therein, syrup jars removably supported in said compartments, a pump and actuating mechanism therefor in each jar adapted to deliver a measured charge of syrup therefrom, a pipe common to all of said compartments and having an independent connection with each of said pumps, a source of fluid pressure connected to said pipe, and a valve for each jar adapted to be operated automatically by the removal of the jar from its compartment to prevent escape of the fluid pressure.

3. A soda fountain apparatus comprising a counter having a plurality of compartments therein, syrup jars in said compartments, pump mechanism for each syrup jar adapted to deliver a charge of syrup therefrom, a pipe common to all of said compartments, a source of pressure supply connected to said pipe, and means for automatically establishing pressure connection between the pump mechanism and said pipe when said mechanism is arranged in operative position in the compartment.

4. A soda fountain apparatus comprising a counter having a plurality of compartments therein, syrup jars in said compartments, pump mechanism for each syrup jar adapted to deliver a charge of syrup therefrom, a pipe common to all of said compartments, a valved nozzle in said pipe in each compartment, and means for connecting said nozzle with said pump mechanism and unseating said valve when said mechanism is arranged in operative position in the compartment.

5. A soda fountain apparatus comprising a counter having a plurality of compartments therein and a top covering said compartments, syrup jars in said compartments and located wholly below said top, guides at the sides of each of said compartments, and pump mechanism supported in said guides and coöperating with each syrup jar to deliver a charge of syrup therefrom.

6. A soda fountain apparatus comprising a counter having a plurality of compartments therein and a top covering said compartments, syrup jars in said compartments and located wholly below said top, guides at the sides of each of said compartments and pump mechanism for each syrup jar supported in said guides beneath the top of the counter to deliver a charge of syrup from the jar.

7. A soda fountain apparatus comprising a counter, a syrup jar compartment in the counter and having guides at its sides, a syrup jar in said compartment, and pump mechanism supported in said jar by said guides.

8. A soda fountain apparatus comprising a counter, a syrup jar compartment in said counter and having guides at its sides, a syrup jar in said compartment, and pump mechanism comprising a plate engaged with said guides to support the pump mechanism in said jar.

9. In a soda fountain apparatus, the combination with a counter, of a syrup jar removably supported therein, pump mechanism for the syrup jar comprising a charge chamber, a plunger operating in said chamber, a piston for operating said plunger, means to supply fluid pressure for actuating said piston, and means automatically operated by the removal of the jar from the

- counter to prevent escape of the fluid pressure.
10. A soda fountain apparatus comprising a counter, a syrup jar therein, pump mechanism for said jar comprising a charge chamber, a plunger operating in said charge chamber, a pressure chamber, a piston operating in said pressure chamber, a valve chamber connected with a source of fluid pressure supply and also connected with said pressure chamber, a valve operating in said valve chamber for admitting pressure to the pressure chamber and means for supporting said pump mechanism independently of said syrup jar.
11. A soda fountain apparatus comprising a counter, a syrup jar therein, pump mechanism for said syrup jar comprising a charge chamber, a plunger operating in said charge chamber, a pressure chamber, a piston operating in said pressure chamber, a valve chamber connected with a source of fluid pressure supply and with said pressure chamber and having an exhaust port, and a double piston valve operating in said valve chamber to normally establish communication from the pressure chamber to said exhaust port and adapted to be operated to close said communication and admit pressure to said pressure chamber to operate the piston.
12. A soda fountain apparatus comprising a counter, a pipe therein connected with a source of fluid pressure supply and having a nozzle, a valve in said nozzle, a syrup jar, and pump mechanism for the syrup jar comprising a socket adapted to receive said nozzle and means for unseating said valve when the socket and nozzle are engaged.
13. A soda fountain apparatus comprising a counter, a pipe therein connected with a source of fluid pressure supply and having a nozzle, a spring-pressed valve for said nozzle normally closing the same and having a stem projecting beyond the end of the nozzle, a syrup jar, and pump mechanism for said syrup jar adapted to be connected with said nozzle and unseat said valve.
14. A soda fountain apparatus comprising a counter, a pipe therein connected with a source of fluid pressure supply and having a nozzle, a valve for said nozzle, a syrup jar, and pump mechanism for said syrup jar

comprising a valve chamber, and means for connecting said valve chamber and said socket and for unseating the nozzle valve to admit pressure to said valve chamber.

15. A soda fountain apparatus comprising a counter having a syrup jar compartment therein, a syrup jar in said compartment, a door at the front of said compartment, and pump mechanism arranged in said syrup jar and comprising a face plate to close that portion of the front of the compartment above said door.

16. A soda fountain apparatus comprising a counter having a syrup jar compartment therein, a syrup jar in said compartment, a door at the front of said compartment, pump mechanism arranged in said syrup jar and comprising a face plate to close that portion of the front of the compartment above said door, a discharge nozzle, and an operating knob projecting through said face plate.

17. A soda fountain apparatus comprising a counter having a syrup jar compartment therein and guides at its sides, a fluid pressure supply pipe in said compartment, a syrup jar adapted to be arranged in said compartment, and pump mechanism in the syrup jar adapted to be inserted therewith in the compartment and engaged with said guides and connected with said fluid pipe in one operation.

18. A soda fountain apparatus comprising a counter, a syrup jar supported in said counter, means for delivering syrup from the jar, a pressure supply pipe, and means for automatically establishing pressure connection between said pipe and the syrup delivery means when said means is arranged in operative position in the counter.

19. A soda fountain apparatus comprising a counter, a plurality of syrup jars supported in said counter, means for delivering syrup from each jar, a pressure supply pipe having a branch for each jar, and means for automatically establishing pressure connection between the syrup delivery means of each jar with its branch pressure pipe when said means is arranged in operative position in the counter.
